UNITED STATES PATENT OFFICE.

WILLIAM H. STIMPSON, OF WINTHROP, MASSACHUSETTS, ASSIGNOR TO
GEORGE A. BODWELL AND W. HOWARD McCONNELL, OF LYNN, AND
HENRY W. SHUGG, JR., OF ASHMONT, MASSACHUSETTS.

WICK-ADJUSTING DEVICE FOR LAMPS.

SPECIFICATION forming part of Letters Patent No. 623,931, dated April 25, 1899.

Application filed April 23, 1898. Serial No. 678,553. (No model.)

To all whom it may concern:

Be it known that I, WILLIAM H. STIMPSON, of Winthrop, in the county of Suffolk and State of Massachusetts, have invented an Improvement 5 in Wick-Adjusting Devices for Lamps, of which the following description, in connection with the accompanying drawings, is a specification, like letters and numerals on the drawings representing like parts.

10 This invention has for its object the production of a novel and simple wick-adjuster for oil-lamps particularly adapted for use in connection with a lamp of the type shown in United States Patent No. 545,313, granted 15 August 27, 1895.

I have herein shown and described my invention as applied to a lamp such as shown in the patent referred to, though my invention is not necessarily limited thereto.

20 Figure 1 represents in vertical section a lamp provided with a wick-adjuster embodying my invention. Fig. 2 is a front elevation of the wick-adjuster applied to the end of a wick-tube; and Fig. 3 is an enlarged transverse sectional view of the wick-adjuster on the line $x x$, Fig. 1.

Referring to Fig. 1, the oil-reservoir A, the neck supporting the bulb c of the wick-tube c^2 and having at its top the burner c' , the 30 wick f within the tube and terminating at the burner, and the outer globe or shade b are and may be all substantially as shown and described in the patent referred to.

My wick-adjuster (shown separately in Fig. 35 2) comprises an expandible body portion d , made herein as a longitudinally-slotted cylinder, preferably of metal, connected by a neck d' with a substantially tubular wick-guide d^2 , the latter having laterally-extended 40 parallel ears d^3 on the side opposite the neck d' . The wall of the wick-guide d^2 is preferably flattened at d^4 below the neck, as clearly shown in Fig. 3, and opposite this flattened portion the wick-actuator is located, shown 45 as a spur-wheel or sharply-notched disk d^5 , mounted between the ears d^3 to rotate on a pin 5.

Referring to Fig. 3, it will be seen that the space between the flat wall d^4 of the wick- 50 guide and the periphery of the spur-wheel is

quite small, to thereby insure at all times the engagement of the spur-wheel with the wick, the flattened part of the wick-guide providing a support for the wick against the thrust of the controlling-wheel d^5 .

The body d of the device is adapted to be sprung upon the lower end of the wick-tube c^2 , as shown in Figs. 1 and 2, whereon it is firmly held by frictional engagement, one or more inturned lugs or stops 3 on the inner 60 end of the body engaging the end of the wick-tube and preventing the body from being pushed far enough upon the wick-tube to bring the latter into engagement with the wick-actuator d^5 . The wick-guide d^2 guides 65 the wick along into engagement with the actuator d^5 , whence the wick passes along the neck d' into the end of the wick-tube.

In order to adjust the wick, the wick-tube is lifted from the reservoir, and a light touch 70 of the finger on the exposed periphery of the actuator will operate to raise or lower the wick as desired.

By reason of the resiliency of the body d the wick-adjusting device is readily applied 75 to the wick-tube and is firmly held in place thereon.

The connection of the wick-guide and body by the narrow neck d' permits free access of oil to the wick between the actuator and the 80 end of the wick-tube and also serves to maintain the support for the actuator sufficiently separated from the body and the end of the wick-tube to permit perfect operation of the actuator.

Having fully described my invention, what I claim, and desire to secure by Letters Patent, is—

1. A wick-adjusting device comprising a body portion, a limiting-stop thereon, a connected wick-guide, and a rotatable wick-actuator mounted on and to enter the guide to engage the wick, a portion of the periphery of the actuator being exteriorly exposed to be engaged by the fingers, to operate, substantially as described. 85

2. A wick-adjusting device comprising an expandible attaching-body, an adjacent tubular wick-guide having integral lateral ears and its walls flattened interiorly between said 100

ears, and a spur-wheel rotatably mounted between the ears to enter the wick-guide between them to engage the wick between the periphery of said spur-wheel and the flattened wall, substantially as described.

3. A wick-adjusting device comprising a body portion, a separated, connected tubular wick-guide having a portion of its wall flattened, and a rotatable wick-actuator mounted on the guide opposite said flattened wall por-

tion to engage the wick between the flattened portion of the guide and the periphery of the actuator, substantially as described.

In testimony whereof I have signed my name to this specification in the presence of 15 two subscribing witnesses.

WILLIAM H. STIMPSON.
